UNITED STATES PATENT OFFICE.

WILLIS G. DODD, OF SAN FRANCISCO, CALIFORNIA.

DESIGN FOR A FRAME FOR ORE-STAMP BATTERIES.

SPECIFICATION forming part of Design No. 27,479, dated August 3, 1897.

Application filed September 23, 1896. Serial No. 606,794. Term of patent 14 years.

To all whom it may concern:

Be it known that I, WILLIS G. DODD, a citizen of the United States, residing in the city and county of San Francisco, State of California, have invented and produced a new and original Design for a Frame for Ore-Stamp Batteries, of which the following is a specification, reference being had to the accompanying drawing, showing a part thereof.

- 10 The frame is composed of the base A and the side uprights B. These uprights are united by the plates d, the said uprights extending through the guides a² of said plates. The side uprights extend through the ears a', 15 projecting from the mortar A', secured to the base-plate, and fit within the ears b, laterally projecting from the base-plate. The side standards are held in place within the ears a' and b by the set-screws b³ and b².

To each side standard is fastened the guide-collar C, which collars support the bearing-boxes C', formed integral therewith.

To the upper end of each side upright is secured the tie-rod cap E².

Having thus described my invention, what I claim as new, and desire to secure protection in by Letters Patent, is—

The design for the frame of an ore-stamp battery, substantially as shown and described.

In testimony whereof I affix my signature, 30 in the presence of witnesses, this 31st day of August, 1896.

WILLIS G. DODD.

In presence of—

N. A. ACKER,
M. G. LOEFLER.
